UNITED STATES PATENT OFFICE

GORDON EVERETT WEIR, OF BAYSIDE, NEW YORK, ASSIGNOR TO TYPICALCULATOR, INC., A CORPORATION OF NEW YORK

CALCULATOR

Application filed September 26, 1927. Serial No. 221,928.

My invention relates to calculators and is more particularly concerned with calculators intended to be used by persons engaged in typographical, advertising and similar work.

The typographical art is now reduced to an exact science. Beautiful medieval script and book titles have been copied by modern type designers and adapted to American type scales. The advertiser of today has at his command the finest type styles of all the ages. His medium of expression is without limit. In the choice of his type set-up he can put behind his message the exact atmosphere necessary to make that message most effective.

While there is no guess work in the composing room of modern printing establishments, from the largest to the smallest, the advertiser copy-writer according to present day methods, continues to guess at the amount of copy a specially designed vehicle is to carry, or more frequently, writes his copy first and thereafter tries to fit it to the allotted space. Or, if he is especially careful he will tediously count the number of words per copy line; multiply this by the number of lines; figure the word capacity of the allotted space, and thereafter—trust to luck. This results sometimes in shortages, but more frequently in over-runs and auditors' corrections and revamping.

To quote from Carl Greer's authentic and valuable work, "The Buckeye Book of Direct Advertising", the only way at present of estimating the amount of copy necessary to fill a set or given space in a layout is: "To estimate the amount of printed space required for a given amount of copy, or conversely, to ascertain the amount of copy required to fill a given type space, count the words on one page of copy. Then count the words on one page of the type to be used. To ascertain the number of printed pages required, multiply the number of words on a page or copy by the number of pages of copy and divide by the number of words on one printed page. * * * The results given are, of course, approximate, but usually sufficiently accurate." Notwithstanding the above well recommended and more or less frequently practiced suggestions, the fact remains that nine times out

of ten they prove to be absolutely inaccurate and are often the cause of costly over-runs, not to mention the tediousness of such a process and the prodigal waste of time required to complete the finished layout. Over-runs, without question, cost large publishing houses hundreds, if not thousands, of dollars, each year.

The calculator of the present invention is designed to make it possible for the copy-writer, with a minimum knowledge of type and typographical composition, to be as accurate as the compositor himself. The linotype and monotype machines are the instruments in the hands of the compositor. The typewriter, an equally exact machine, is the instrument in the hands of the copy-writer; and the calculator (as hereinafter more fully explained) is the link or instrument bridging and connecting these two machines. Being mathematically accurate, the calculator if properly used, makes it possible for the copy-writer to determine in advance the area required to be filled in on the typewriter for similarly filling a given space allotted to a given size and style of type, or vice versa. The advantages of such a device or instrument are obviously manifold.

In the drawings, wherein like reference characters denote like or corresponding parts.

Fig. 1 is a plan view of the calculator complete;

Fig. 2 is a longitudinal vertical sectional view on the line 2—2 of Fig. 1;

Fig. 3 is a transverse vertical sectional view on the line 3—3 of Fig. 1;

Fig. 4 is a similar view on the line 4—4 of Fig. 1;

Fig. 5 is a plan view of the so-called "depth" scale flattened out;

Fig. 6 is a plan view of the so-called "width" scale flattened out;

Fig. 7 is a diagram of a layout in which the actual type and illustration space for the required set-up are clearly shown, and

Fig. 8 is a diagram of the same layout, the area allotted to typewritten matter having been determined by means of the calculator;

which area, it will be noted, is different from that indicated in Fig. 7.

In the embodiment of the invention selected for illustration only the preferred form of the invention is shown. Preferably the calculator comprises a body portion A of wood or other suitable material in which two parallel longitudinally extending grooves B and B¹ are formed. These grooves B and B¹ extend throughout substantially the full length of said body portion and are open at the top thereof to expose or render visible the depth and width scales C and D which are housed respectively within said grooves. The scales, in cross-section, are cylindrical, and in the operation of the calculator, are adapted to be rotated as well as moved back and forth longitudinally of said grooves. The scale C adjacent to the top edge of Fig. 1 will be hereinafter referred to as the "depth scale", whereas the scale D adjacent to the bottom edge of said figure will be hereinafter referred to as the "width scale." Except for the exterior markings upon them the scales C and D are the same.

At one end of the body portion A an end plate E is provided. Said plate E has formed therein suitable openings E¹ thru which the scales C and D extend. Each scale at its extended end has formed thereon a knob F by means of which it may be conveniently grasped and either rotated or slid. Preferably the scales C and D are hollow throughout. Each (see Fig. 2) is mounted 30 on a suitable guide or core G which at one end is carried beyond the corresponding end of its associated scale to enter an end casing H fastened to that end of the body portion A remote from the end plate E. The cores 35 G, the incapable of sliding movement, are rotatable with said scales. By forming the cores G of polygonal section and providing at the inner end of each scale a similarly shaped opening G¹ (thru which the cores extend), any turning movement given the scales 40 will be directly imparted to said cores. To hold the cores G against sliding movement, bushings H¹ mounted on the cores and engaging in seats H² formed in the casing H, 45 are provided.

As it is intended that the scales C and D shall be rotated in one direction only, suitable pawl and ratchet mechanism is provided at one end of each scale. The ratchets I, in 50 each instance, are mounted on the cores G, between the bushings H¹ and within the end casing H. The pawls I¹ are likewise mounted within the end casing H and are adapted to engage with the ratchet teeth. The pawls 55 are gravity actuated and are mounted for vertical sliding movement in suitable guides I² positioned one each, at opposite sides of the pawls. Since the pawls I¹ are at all 60 times in engagement with the ratchet teeth, and since the ratchets I are thus held against

rotation in a reverse direction, obviously accidental or unintentional rotation of the scales C and D is prevented.

In addition to the grooves B and B¹ in which the scales C and D are housed, there is provided also a center groove K. This groove K, however, does not extend throughout the full length of the body. Within said groove K a tongue K¹, fastened on the underside of a slide L, is fitted to slide back and forth; the cross-sectional shape of the tongue and groove being such that the slide is held in place. Said slide L is adapted to overhang the width scale D and has formed therein an opening L¹ thru which the markings on said scale can be seen. It is provided also with a second and larger opening L² thru which the markings on the top face of the body can be seen and with which an indicator or pointer L³, formed on the margin of said opening, is 70 adapted to register. The purpose and nature of the markings on the scales and body as well as the relationship existing between said markings and the slide L, will be hereinafter 75 pointed out. If desired, a magnifying glass L⁴ may be fitted and held within the opening L¹ to better visualize the scale markings which are of necessity exceedingly small.

The "great scale" markings, which are the markings along the opposite longitudinal edges of the body portion A, are designated as M and M¹. These markings indicate inches and fractions thereof and are preferably carried in extent throughout the full 80 length of the instrument which may or may 85 not be 12" long.

The markings on the depth scale C are based on the type point system now generally employed. In Fig. 5 is illustrated the eight scales comprising said depth scale. These 90 scales, are designated respectively as O, O², O⁴, O⁸, O⁷, O⁶, O⁵ and O¹. For an understanding of the units used in the marking of the several scales, the following table is 95 given:

Scales 0—1"	—6 pt. scale	—12 pt. and 72 pt. rules
Scales 0— $\frac{5}{16}$ "	—	—60 pt. rule
Scales 0— $\frac{23}{32}$ "	—7 pt. and 36 pt. scales	—48 pt. rule
Scales 0— $\frac{7}{12}$ "	—	—30 pt. scale —42 pt. rule
Scales 0— $\frac{13}{12}$ "	—8 pt. and 24 pt. scales	—
Scales 0— $\frac{13}{16}$ "	—9 pt. and 18 pt. scales	—
Scales 0— $\frac{13}{16}$ "	—16 pt. scale	—
Scales 0— $\frac{13}{16}$ "	—10 pt. and 14 pt. scales	—

The 72, 60, 48 and 42 point types are the large "display" types (sizes) and will rarely be found except in single line captions. If called for, the letter depth of these large display types can be conveniently measured by an ordinary rule. Any scale, therefore, the unit of which is the actual or closely approximate depth of a given line of this point size, becomes for such size simply a line depth 100 rule instead of a column depth scale. Hence the use of the terms "point scale" and "point rule" in the table. For example, the scale O (whose unit is 1") acts as a plain rule for 72 point type, which is 1" deep per line. It 105

likewise acts as a column depth rule for 12 point type, since the depth of 12 point type is identical with that of the typewriter. Typewriter type are invariably in 12 point size.

To find the number of lines per inch of any point size, divide that point size into 72, e. g., 12 point type is 72 divided by 12 or six lines to the inch; 8 point type is 72 divided by 8 or nine lines to the inch; 6 point type is 72 divided by 6 or twelve lines to the inch; 7 point type is 72 divided by 7 or ten and two-sevenths lines to the inch (for all practical purposes figured as an even 10); 9 point type is 72 divided by 9 or eight lines to the inch); 14 point type is 72 divided by 14 or five and one-seventh lines to the inch (for all practical purposes figured as an even 5); and so on. To eliminate the use of four extra scales, the practical figure instead of the actual mathematical figure is used in the case of 7, 10, and 14 and 30 point sizes, as in actual practice, this will work no inaccuracy in the copy column depth. Any slight variation encountered is taken care of in the actual set-up by a slightly wider spacing between lines.

The 6, 7, 8, 9 and 10 point types are smaller in size than the 12 point or typewriter type size. These point type therefore have more lines to the inch than six which is the number of lines per inch for typewriter type. The scales therefore marked for 6, 7, 8, 9 and 10 point type are adding scales, i. e., scales to be used in ascertaining the column depth where set-up type smaller in size than typewriter type are specified. Where type larger than typewriter type are specified, the scales marked for 14, 16, 18, 24, 30 and 36 point sizes are used. Here, however, the scales instead of being adding scales are subtracting scales, since the lines per inch of column depth are less (where the point size is greater than 12) than six lines to the inch, the number of lines per inch in 12 point or typewriter size. For example: take the $\frac{1}{2}''$ scale O⁴ with the 8 point (add) and 24 point (subtract) scale. On a 1'' copy depth there would be six lines for 12 point (typewriter) size, nine lines for 8 point size; or three lines for 24 point size. 8 point converted into 12 point would be $1\frac{1}{2}''$ (6 plus 3). 24 point converted into 12 point would be $\frac{1}{2}''$ (6 less 3).

The width scale D, the similar to the depth scale, is based on the decimal system. Its scales (13 in number), designated respectively as P, P¹, P², P³, P⁴, P⁵, P⁶, P⁷, P⁸, P⁹, P¹⁰, P¹¹, P¹², are, with the exception of the scale P¹², in units respectively of 1.7, 1.3, 1.2, 1.9, .8, .7, .6, .5, .4, .3, and .2 inches reading from left to right, Fig. 6. The scale P¹² is marked in $\frac{1}{6}''$ units for converting from standard typewriter (ten characters to the inch) to Elite typewriter (twelve characters to the inch). After the required width

in standard is found, the scale P¹² is merely used to subtract $\frac{1}{6}$ of the standard width, thus converting standard width into Elite. Mathematically this would be figured as follows: If 10 standard equals 12 Elite, 1 standard equals $1\frac{1}{5}$ Elite or, vice versa, 1 Elite equals $\frac{5}{6}$ standard. Hence standard minus $\frac{1}{6}$ standard equals Elite.

To illustrate the function of the remaining scales comprising the width scale D the following may be noted. 6 point Cloister type (lower case) has 27 characters to the inch. To convert to standard typewriter (10 characters to the inch) the scale P is used. This scale adds 1.7 times the layout width to itself for standard, e. g., 1'' of 6 point layout equals 1'' plus 1.7'' or 2.7'', the length of line (width) required by standard typewriter for 27 characters. Likewise two layout inches in six point equals 2'' plus 3.4 or 5.4'', the length of line (width) required by standard typewriter for 54 characters. Similarly for 48 point (the .6 scale or scale P⁷) 1'', 48 point layout width equals 1'' less .6 or $\frac{2}{3}''$ of standard, as 48 point Cloister has four characters to the inch. Regardless of the scale used (it may be a scale of the depth scale C) the reading obtained therefrom, when properly added to or subtracted from (as the case may be) one or the other of the great scales M or M¹ will indicate accurately the area variation required in the conversion of layout areas to copy areas or vice versa. For addition, the zero end of the great scale is placed at one edge (or at the top) of the type layout space with the scale extending across the space. The zero end of the sliding scale to be used is then slid to the other edge of the layout space and aligned with the reading on the great scale which indicates the width (or depth) of the type layout space. The reading on the sliding scale corresponding to the indicated reading on the great scale is naturally aligned with a higher reading on the great scale. This higher reading on the great scale is the width or depth (as the case may be) of the required typewriter copy space. For subtraction the sliding scale used is slid until the reading on the great scale and the corresponding reading on the sliding scale are together. The desired width (or depth) is then the sliding scale zero.

As a means for quickly and accurately determining the width (characters per linear inch) of any given style type, further designations R are provided (preferably in red) on the scales of the width scale D. These designations R, which are point size designations, together with other and further designations S and T (likewise in red) bear a certain definite relationship. Since various styles of type, while standard, (the point system) as to depth, vary greatly in width of character, they (the various styles) have been grouped alphabetically. The designations S, 130

which are the alphabetical grouping designations, are shown for one style type only, to wit, f. This showing is carried out for the major groupings T also. The major groupings are preferably made for "lower case", "italics" "Bold" and "caps"; each major grouping having its associated alphabetical grouping spaced from the next adjacent major group. For each major grouping, as well as for each alphabetical grouping, a column or line of figures of the same order as the column f are provided. With these designations R, S and T, the slide L is used.

To explain the utility of the designations R, S and T, it may be assumed that a layout copy is made or received by the copy-writer, such copy having indicated thereon the style and point size type to be used in the finished piece. For example: Cloister—6 point—lower case. The copy-writer then by shifting the slide L along the groove K to the alphabetical column f, lower case, can, by turning the scale D until the 6 point designation appears beneath the magnifying glass L⁴, ascertain which scale of the vertical scale D should be used in calculating or computing the column width. This computation having been made, the depth computation can be similarly made by manipulating the 6 point scale of the scale C. The indicator L³ within the opening L² when brought into coincidence with the alphabetical designation desired, will invariably line up the magnifying glass with the character designation R. For convenience, "add" and "subtract" indications may be associated with the designations R if desired.

Between the conceived idea and the printed product resulting therefrom, there are ordinarily three steps (1) the layout; (2) the copy; and (3) the finished piece. The use of the calculator calls for no additional steps. It simply converts by areas, from the desired type size and style (which vary greatly) to a known constant, i. e., that of the typewriter. In other words, it takes care of the variable factor of type variations and converts from the fixed space allotted on the layout to the other or invariable quantity—the typewritten copy necessary to fill that allotted space with the selected type size and style. Being based on character widths and point column depths, it is essentially and unfailingly accurate when properly used.

In Fig. 7 is illustrated, an actual layout (step 1) and in Fig. 8 is illustrated a page of copy (step 2). The layout usually consists of a pencil sketch of the actual type space V and illustration space V¹. The latter may or may not be required. Where there is an initial letter, the initial letter space can be blocked off as indicated at V². To convert the layout areas V, V¹ and V² (Fig. 7) to the areas required for the copy (assuming that a typewriter having standard or 12

point type is used in making the copy) it is only necessary for the layout to specify what style and type point size are to be used in the set-up of the finished piece. With the calculator, these unknown or converted areas can be quickly ascertained. Fig. 8 shows clearly the area required to be filled in on the typewriter when the layout copy specifies, for instance: Type style—Goudy-Garamond; type size—12 point. In Fig. 8 the areas corresponding with the area V, V¹ and V² of Fig. 7 are designated respectively as W, W¹ and W². In this particular instance only the width area is varied, since the type size (12 point) corresponds in depth with typewriter size type.

From the above, taken in connection with the accompanying drawings, it is obvious that with a given layout, made either before the copy is written or vice versa, and by means of the calculator, the depth and width of each section of copy (or the whole if not using many diversified types) in the desired type point size may be instantly converted into either standard or Elite typewriter type and with this new or computed area drawn out in its new proportions on a blank sheet inserted in a typewriter and the copy typed in the space outlined, such typed matter will exactly fit the copy on the layout. The type copy then is an exact specimen of the type as it will finally appear in the finished piece. The first proofs therefore will always be final proofs and much time and labor, as well as cost, thereby saved.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:

1. An instrument of the character specified comprising a body, a rotatable member carried by said body, characters designating type styles indicated on said body, circumferentially spaced characters designating different type point sizes indicated on said member, said type style designations and said type point designations being so relatively arranged that in turning said member the circumferentially spaced designations will be made to successively coincide with the characters designating type styles.

2. In an instrument of the character specified, an elongated body having formed therein a longitudinally extending substantially cylindrical groove, a rotatable and longitudinally slidable substantially cylindrical hollow member engaging in said groove, a core of polygonal section engaging in the hollow of said member, said core being rotatable in one direction only, means engaging said core

to prevent its sliding movement with said member, and means engaging said core to restrict its rotation as aforesaid.

3. Apparatus for accurately and quickly determining a required dimension of typewritten copy which, when converted into print of any one of a plurality of different sizes and kinds of type will exactly fill a corresponding given dimension of the print space, comprising a rule for measuring the corresponding dimension of the desired print page, a reference point indicated on said rule, a scale also indicated on said rule, and means for cooperating with said scale and forming a part of said rule for indicating the points on said rule located the exact distances from the reference point thereof corresponding to the different dimensions of typewritten copy required for different sizes and kinds of type.
- 20 4. Apparatus for determining a dimension of an area required to be filled in on a typewriter to exactly fill a given space allotted to a given size and style of type which comprises, means for measuring the linear dimension of said given space, and means cooperating with said first named means for ascertaining the corresponding dimension of the area to be filled on the typewriter, one said means being capable of movement both longitudinally and rotatably in its relation to the other.
- 25 5. Apparatus for accurately and quickly determining a required dimension of the print space which a given amount of typewritten copy when converted into print of any one of a plurality and different sizes and kinds of type will exactly fill, comprising a rule for measuring the dimension of the given typewritten copy, a reference point indicated on said rule, a scale also indicated on said rule, and means for cooperating with said scale and forming a part of said rule for indicating the points on said rule located the exact distances from the reference point thereof corresponding to the different resultant dimensions of print space for different sizes and kinds of type.
- 30 6. A slide rule, comprising an elongated body having formed therein a longitudinally extending cylindrical groove, a rotatable and longitudinally slidable substantially cylindrical member engaging in said groove and formed with a non-circular hollow, a core of
- 35 non-circular section rotatable with and engaging in the hollow of said member whereby the core is compelled to rotate with the hollow member, means engaging said core to prevent its longitudinal sliding movement,
- 40 means comprising a ratchet to limit the rotation of the core and hollow member to a single direction and to aid in accurately positioning the member at any one of a plurality of selected positions, scales indicated on the
- 45 elongated body, and on the hollow member,

and means for rotating and sliding the hollow member within the elongated body.

In testimony whereof, I hereunto affix my signature.
